UNITED STATES PATENT OFFICE.

VICTOR BÉLANGER, OF MARSHFIELD, MASSACHUSETTS, ASSIGNOR TO NEW ERA SPINNING CO., OF BOSTON, MASSACHUSETTS, A CORPORATION OF MASSACHUSETTS.

DEVICE FOR SPINNING AND TWISTING TEXTILE FIBER.

1,285,598.

Specification of Letters Patent. Patented Nov. 26, 1918.

Application filed September 7, 1911, Serial No. 648,152. Renewed April 10, 1918. Serial No. 227,821.

To all whom it may concern:

Be it known that I, VICTOR BÉLANGER, citizen of the United States, and resident of Marshfield, Massachusetts, county of Plymouth, have invented certain new and useful Improvements in Devices for Spinning and Twisting Textile Fiber, of which the following is a specification.

This invention relates to machines for spinning or twisting textile fiber and is in the nature of an improvement on the invention set forth in my co-pending application for United States Letters Patent Serial No. 595,187, which was characterized by a reciprocating yarn-engaging cap slidingly mounted on the spindle member by which it was rotated.

One of the features of the present invention consists in an entirely new construction of the traverse or builder rail, whereby the entire rail is located behind the spindles so that it does not obstruct in any way access to the spinning members. Another feature of the invention consists in the utilization of the movable doffing rod or bar by which the yarn is held in proper position to facilitate the doffing operation. Further features of improvement reside in the construction of the spinning cap and also in the construction of the supporting wheel upon which the cap pivots during the operation of spinning. A new arrangement and construction of the separator mechanism is also a feature of the present invention.

In the accompanying drawings I have illustrated the preferred modes of embodying the principles of this invention.

Figure 1 is a front elevation illustrating so much of the spinning machine in conjunction with my invention as is necessary to understand the relation of the present improvements thereto.

Fig. 2 is an end elevation of the same partly in section taken transversely of the machine.

Fig. 3 is an enlarged elevation showing the spindle, the spinning cap and its supporting means.

Figs. 4 and 5 are detail views illustrating the improved construction of the yarn engaging cap.

Figs. 6, 5^a, 7, 8, 8^a, and 9 are detail views showing the construction and arrangement of the pivot wheel which supports the cap.

Fig. 10 is an end elevation illustrating the

location of parts during the operation of doffing.

Fig. 11 is a front elevation of the traverse rail showing the doffer rod guide.

Fig. 12 is a plan view of a portion of the 60 builder or traverse rail showing also the arrangement of the separators.

I have shown the invention applied to a common type of spinning frame which is, however, modified as will be hereinafter 65 pointed out to meet special conditions and obtain certain desired advantages. The vertical end frames *a*, the roller beam *b* and the spindle supporting rail *c*, may be of the usual construction common in or suitable to 70 spinning frames or cap frames. The thread-board *b'* and the eye-blocks *b*² are also of the usual construction but where the rail is given a long traverse to build a long bobbin as high as possible, I prefer to set the thread-eye *b*³ somewhat in advance of the central axis of the spindle, for reasons to be herein- 75 after explained.

The traverse or builder rail instead of being a flat rail with spindle holes bored therein at regular intervals through which the spindles pass, is made in the form of a hollow rail or tube *d*, whose interior forms an oil reservoir which may be conveniently 80 filled through a short oil tube *d'*. At regular intervals, according to the space separating the spindles, the top face of the rail *d* is provided with a series of openings or holes to receive the bolsters *e* which form the bearing supports for the rotary pivot wheels *f* 85 which support the cap *g*. This bearing bolster *e* may be of any suitable construction to form a self-lubricated bearing for the journal or supporting pin *f'* of the pivot wheel. As best shown in Fig. 8 the bolster 90 parts are provided with holes communicating with the interior reservoir formed in the rail *d* to permit the flow of oil to the interior of the bolster in order to keep the journal or step bearing well lubricated.

The cap *g* is preferably funnel-shaped or cup-shaped and has inside of its upper end a bushing or coupling member *g'* which fits easily into the upper end of the cap but is separated therefrom by an annular piece of 105 textile fiber tape *g*² or other material suitable to minimize the transmission of vibration from the coupling member to the cap. I prefer to connect this coupling member or sleeve *g'* with the cap by means of a pin or 110

equivalent means that will admit of a slight vertical play between the members. The form of connection herein shown comprises a slit ring g^3 of a size that will normally contract upon the outside of the cylindrical portion of the cap which is grooved to receive it, one end of said ring being bent inwardly to pass through the cap and enter a hole formed in the exterior of the coupling member or sleeve as shown in Fig. 5. The coupling member itself is preferably provided on the inside with a spline or key to engage a vertical groove or keyway formed in the bobbin or spindle member h . This key instead of being made integral may be made in the form of a circular sheet metal spring g^4 which is made of a size to be forced inside of the bore of the sleeve g' where it expands into an annular groove 20 adapted to receive and retain the key ring g^4 .

To reduce the ballooning of the revolving yarn and to prevent its kinking, I provide the lower portion of the cap g with an annular projecting flange g^5 adapted to engage 25 the revolving yarn as indicated in Figs. 2 and 6 to hold it away from the body portion of the cap.

I prefer to make the lower yarn-engaging edge of the cap of somewhat smaller diameter than the largest diameter of the body portion and in order to make the cap of variable length, according to the length of the "chase" of the cap, I make this narrower lower portion in the form of a separate annular member g^6 formed with an annular shoulder or offset and having also an upwardly extending flange g^7 which is slotted to make it compressible in order that it may be forced into firm engagement with the interior of the vertical lower portion g^8 of the cap. As best shown in the enlarged view Fig. 8^a, the flange g^5 is a separate piece shrunk on to the exterior of the cap, while the upturned flange or annular lip g^7 of the lower removable portion is formed with a slight bead g^9 engaging a shallow annular depression formed in the corresponding portion of the interior of the cap.

The form and relative arrangement of the pivot member or bearing wheel is susceptible of suitable variation. In Figs. 8, 8^a and 9 I have shown the pivot member f comprising an upper disk f^3 which may be of wood, metal or compressed fiber and a lower disk f^4 which may be of any similar material and an interposed disk f^5 of relatively yielding material such as felt, cloth, or the like. These three layers or disks are held together by upper and lower metallic flanges f^6 , f^7 60 which are provided with oppositely extending tubular members or flanges having screw-threaded engagement with each other, each flange being provided with spanner holes or equivalent device to enable them to be screwed tightly together in order to pinch

the interposed disks firmly together. In the central tubular portion of the wheel is mounted the bearing pin or journal which has the enlarged head f^{10} to give it adequate supporting engagement with the metal 70 clamping members which hold the parts together. The bolster f^{12} carries an interior perforated bearing tube or box f^{13} whose periphery is vertically fluted to facilitate the flow of oil. The peripheral portion of 75 the disk f^4 is sometimes fluted or grooved as shown in Fig. 9, to form notches to receive the thread. The flange g^5 is arranged so as to rest upon the upper disk f^3 which forms the supporting engagement therewith. The 80 adjacent portions of the pivot wheel and of the cap assume when in normal operation, substantially the relationship indicated in Fig. 8^a, which also indicates the course of 85 the yarn.

In Fig. 6 I have shown a slightly modified construction, in which the cap g is provided with a slightly dished flange g^{20} which is convex on its lower side, while the inserted removable lower extension member g^{21} , instead of being formed with an annular stop or shoulder, is curved inward. In this case the pivot wheel comprises only two disks, namely, an upper disk f^{20} , which may be of wood, fiber, metal or other suitable material, 90 and an under disk f^{21} preferably made of felt, cloth or other shock-absorbing material. The upper disk which engages and supports the flange g^{20} is preferably provided with comparatively deep radial notches, as indicated in Figs. 6 and 5^a, while the outside periphery, except for the rounded contour at the upper edge, is cylindrical so as to afford a lateral support to repel the opposite portion of the cap. The central portion of 100 the disk f^{20} is recessed to form a seat for the head of the pivot pin or journal f^{24} .

It will be noticed that in both forms of pivot wheel and cap, the yarn is deflected from the normal course that it would assume 110 in passing from the outside of the spreading flange to the extreme lower edge of the cap and in such a way as to press it frictionally against the intervening portion of the pivot wheel. This frictional engagement with the pivot wheel is further augmented by notching either the upper or the lower yarn-engaging disk. These notches perform a two-fold function in that they serve in addition to the friction of the yarn 115 against the wheel, to cause the yarn to travel at the same rate of speed as the periphery of the wheel. As the wheel is driven by its frictional engagement with the cap and as there is a substantial amount of slip in this engagement, the wheel rotates at a slower peripheral speed than does the cap and thus serves to act as a drag to retard the speed 120 of revolution of the yarn. The effect of this is to maintain a good tension upon the yarn 130

at all times so as to build a firm and solid cap on the bobbin or spindle. Thus the wheel is made to serve as a means for supporting the cap and disengaging it from frictionally clutching the spindle member and also as a means for retarding the revolution of the yarn so as to give it a proper tension for winding purposes.

By employing this principle of construction I can advantageously dispense with the annular controller shown in my former application above mentioned.

According to the usual practice in ring and traveler spinning, as the builder rail ascends to higher levels, it acts to shorten the length of the ballooning portion of the yarn, thus diminishing the tension of the yarn at the top portion of the bobbin. To avoid this variation in tension, I provide means for lifting the thread-eye progressively as the bottom edge of the cap approaches the upper part of the spindle member o . This may be easily accomplished by securing to the builder rail d an upwardly extending bracket d^{10} arranged in position to engage some portion of the thread-board, such as the lifting handle b^{10} usually provided. As shown in Fig. 11 the bracket d^{10} may be slotted in its lower end to receive the retaining screws so as to render it adjustable. The thread-eyes b^8 may be set to project slightly in front of the central axis of the spindle member so that as the thread-board swings up, the resulting offset of the thread-eye relative to the spindle is divided equally in front of and behind the spindle instead of all being to the rearward of the spindle.

In some cases it may be desired to use separators to keep the ballooning yarn of adjacent spindles from lashing together and breaking down ends. In such case the rail d is formed with a plurality of forward projecting supporting arms d^{12} which form a journal box or bearing for a rock shaft i upon which are mounted the separator blades i' so that the separator mechanism is carried wholly by the traverse rail itself. The separator blades are fixed in hubs i^2 mounted on the rock shaft i and may be pivotally secured thereto in such a way that while all may be thrown out of operative position together or moved into operative position together, each one is nevertheless capable of independent movement from the operative position. This may be accomplished in any suitable way as by providing a series of pins or projections i^3 normally engaging lateral notches formed in the end faces of the hubs i^2 , the hubs being normally pressed into interlocking engagement with said pins or projections by means of springs i^5 which permit each member to be swung into or out of locking engagement with its pin. It will be noticed that with

this construction the separator blades may be dropped down in front of and below the traverse rail even when the rail is at its highest position without lowering the rail. It will be understood that the rail is given its traverse in the usual manner by means of the usual lifting rods d^{20} .

In the doffing operation on ring frames, it is the usual practice to lower the ring rail or traverse rail before removing the full bobbin. In this operation the doffer in the act of removing the full bobbin, draws the free yarn around the spindle and then places a new bobbin on the spindle so as to pinch the yarn inside the bobbin against the spindle, after which the free portion of the yarn next to the full bobbin is broken. In a ring frame the engagement of the traveler serves to carry the free portion of the yarn down as the rail descends but of course applicant's cap cannot descend in this manner over the full bobbin. Consequently, he has devised a special doffing means for carrying down the yarn toward the base of the spindle preparatory to the doffing operation.

A simple form of the invention is shown in Figs. 1, 2 and 10. In this case each vertical support or samson of the frame is provided with forwardly projecting brackets a' which carry longitudinal swivel pins m which are perforated transversely of their axes to receive the ends of a long looped wire rod or bail m' . This bail obviously has a sliding engagement through the swivel pins m and can be swung from its lower position up over the tops of the spindles and dropped to the position indicated in Fig. 10. If desired, the bracket d^{10} may be provided with an additional finger d^{30} to form a guide and rest or support for the doffer wire to hold it in proper position and also out of contact with the pivot wheels. The combined swivel and sliding engagement of the bail m' permits the above described action to be readily performed and of course carries down the bight of the free portion of the yarn between the spindle and the thread-eye to the lower portion or base of the spindle, as indicated in Fig. 10. After the doffer member has been swung into this position and the rail lowered, the operation of doffing is precisely the same as commonly practised in traveler ring frames. The doffer member may for convenience be provided with adjustable stops m^3 which prevent the wire from dropping below a predetermined position when it is lifted for doffing purposes. When the frame is in normal use the doffing member hangs down entirely out of the way.

It will be observed that applicant's construction of the frame and particularly of the rail permits unobstructed access to the spindles for the purpose of replacing slack or broken bands, for oiling and other pur-

poses, and if for any reason it is desired to get access between the spindles when the frame is running, any one of the separator blades may be dropped without disturbing 5 the others and may afterward be restored to operative position. The hollow rail forms a large oil reservoir requiring but very infrequent replenishment and obviates the necessity of oiling each individual pivot from 10 time to time.

What I claim is:—

1. In a machine for spinning and twisting textile fiber, the combination of the rotary spindle members, the yarn-engaging and 15 guiding members by which the building of the cop is effected, and a reciprocatory traverse rail forming a support for the guiding members and lying wholly behind the spindle members, substantially as described.

2. In a machine for spinning and twisting textile fiber, the combination of the rotary spindle members, a traverse rail located behind the spindle members so as to afford unobstructed access to the spindles from the 25 front, yarn-engaging members mounted to revolve around the axes of the spindle members, coöoperating supporting members carried by the traverse rail to engage and support the yarn-engaging members, substantially as described.

3. In a machine for spinning yarn, the combination with the spindles and the co-operating caps of the hollow traverse rail forming an oil reservoir, a series of perforated bolsters supported by said rail to permit the oil inside the rail to flow 35 into said bolsters, a series of bearing wheels supported in said bolsters and having supporting engagement with said caps, substantially as described.

4. In a machine for spinning yarn, the combination of the spindle members, the yarn-engaging caps, the anti-friction supporting members for said caps, and a common oil reservoir for supplying oil to lubricate 45 said anti-friction members, substantially as described.

5. In a machine for spinning fiber, the combination of a series of spindle members, 50 yarn-engaging caps coöperating therewith, anti-friction supporting members for said caps, a traverse rail forming a common support for the anti-friction members and provided with an oil conduit communicating 55 with the bearings of each anti-friction member, substantially as described.

6. In a cap spinning frame, the combination with a rotary spindle member, of a rotary cap mounted to reciprocate thereon, 60 an external bearing member arranged to have lateral engagement with the cap, and an annular member surrounding the cap and forming a thrust-supporting connection between the cap and the bearing member, substantially as described.

7. In a cap spinning frame, the hollow cap provided at its lower end with a yarn-engaging downwardly projecting extension member whose lower annular edge is inwardly offset with relation to the greatest 70 diameter of the cap, substantially as described.

8. The combination with the rotary spindle members, rotary caps mounted thereon and driven thereby, a traverse rail, a series 75 of cap-supporting rotary bearing members mounted in the traverse rail, and a series of annular yarn-engaging members encircling the caps and having supporting connection therewith, said annular members being 80 arranged to overhang the peripheral portions of the bearing members by which they are supported, substantially as described.

9. A cap for a spinning frame embracing in its construction a hollow cup-like member provided at its upper end with a central bearing sleeve for slidably engaging a central spindle member, and an annular flange member projecting beyond the periphery of the body of the cap and constructed to have 90 bearing engagement with an external supporting member for the purpose of reciprocating the cap, said flange having a continuous or unbroken yarn-engaging edge, substantially as described. 95

10. A cap for a spinning frame embracing a hollow cup-like member formed at its upper end with a central opening, a tubular bearing sleeve forming a supporting member for the cap located in said central opening, 100 said sleeve being provided with an internal annular recess, and a removable key located inside said recess and having an inwardly projecting tongue to engage a key-way in a coöperating spindle member, substantially as 105 described.

11. A cap for a spinning frame embracing the hollow cup-like member, a bearing sleeve located loosely inside said cup-like member to have a slight vertical play therein, and 110 an annular member located within an interior recess formed in said sleeve and having an inwardly projecting tongue forming a key for engaging a spindle member, substantially as described. 115

12. A bearing wheel for a cap spinning frame, embracing a supporting pin, and a head comprising an upper disk-like member provided with peripheral radially extending notches, and a lower disk of yielding material, substantially as described. 120

13. A bearing wheel for the cap of a cap spinning frame, embracing the central supporting journal and an enlarged annular head whose upper peripheral edge is provided with a series of radial notches to receive and retard the ballooning yarn, substantially as described. 125

14. In a cap spinning frame the combination of the rotary cap provided with an out- 130

wardly projecting circular flange located at some distance above its lower edge, a bearing wheel adapted to engage the under surface of said flange and having also lateral engagement against the periphery of said cap below the flange, substantially as described.

15. In a cap spinning frame the combination of the rotary cap provided with an outwardly projecting circular flange located at some distance above its lower edge, a bearing wheel adapted to engage the under surface of said flange and having also lateral engagement against the periphery of said cap below the flange, said bearing wheel being formed with a series of notches to engage and retard the rotation of the ballooning yarn, substantially as described.

16. In a cap spinning frame the combination of the rotary spindle member, the rotary cap, and a peripheral bearing wheel arranged to partly support said cap and formed with a series of notches to receive and retain the yarn while it is passing between the cap and the bearing wheel, substantially as described.

17. A cap for a cap-spinning frame embracing in its construction a hollow cup-like member open at its lower end and provided at its upper end with an opening of smaller 30 diameter adapted to loosely fit the spindle member, and an annular key of spring metal expanded into frictional engagement with the interior of said upper opening and having an inwardly turned tongue for engaging a groove in the spindle member, substantially as described.

18. A cap for cap-spinning embracing in its construction a hollow cup-like member whose upper end is formed with a central 40 bore corresponding approximately to the diameter on the spindle member, an annular key member having frictional engagement with the said bore, said key member being formed to engage a spline in the spindle 45 member, substantially as described.

In witness whereof, I have subscribed the above specification.

VICTOR BÉLANGER.
